UNITED STATES PATENT OFFICE.

CHARLES T. SCHOEN, OF SEWICKLEY, PENNSYLVANIA.

APPARATUS FOR DISHING AND ROUNDING STEEL CAR-WHEELS.

SPECIFICATION forming part of Letters Patent No. 789,633, dated May 9, 1905.

Application filed October 5, 1904. Serial No. 227,285.

To all whom it may concern:

Be it known that I, CHARLES T. SCHOEN, a citizen of the United States, residing at Sewickley, in the county of Allegheny and State 5 of Pennsylvania, have invented a certain new and useful Improvement in Apparatus for Dishing and Rounding Steel Car-Wheels, of which the following is a full, clear, and exact description.

10 In rolling steel car-wheels it is not always possible to produce them with perfectly circular treads, and resort, therefore, must be had to some milling-machine to true the treads that are not thus circular. The skin 15 formed by rolling renders the tread more durable and otherwise more satisfactory than is a tread dressed by milling or other operation which removes such skin, and, moreover, the milling operation adds an element of cost 20 to production which it is important to avoid from a commercial view-point.

I have found that the inaccuracies in the circularity and diameter of rolled-steel car-wheels and any slight changes in the contour 25 of the wheel-tread which might be occasioned by dishing the wheel may be effectively and economically corrected and the skin retained whole by subjecting the wheel while hot to the action of a circular collapsible die applied 30 to the rim or tread, which serves to reduce it to a practically true circle. This operation is performed preferably after the wheel has been dished and is a sequence to that operation and in connection with the dies for performing it.

35 The invention comprises a circular die composed of a series of segments of the contour or profile of a wheel's rim or tread and adapted to be converged or collapsed about a 40 wheel, so as to correct any of the aforesaid inaccuracies, as I will proceed now more particularly to set forth and claim.

In the accompanying drawings, illustrating the invention, in the several figures of which 45 like parts are similarly designated, Figure 1 is a plan view of the lower die or matrix. Fig. 2 is a vertical section of a pair of dies, including the matrix of Fig. 1, for dishing and truing rolled car-wheels. Fig. 3 is a 50 vertical section of the same dies, omitting the

segmental die-operating ring and as used for dishing the wheel.

The matrix 1 is shaped to receive the hub and web and outer face of the rim of a car-wheel. The male die 2 is complementally 55 shaped to give to the wheel in the matrix the requisite dish or flare. This dishing operation and the next subsequent operation of truing the rim or tread are performed while the wheel is hot. To get these operations 60 into as quick sequence as possible and while the wheel is hot and without requiring reheating, I provide the matrix with a circumferential ring 3 on a support 4, having an annular groove 5 in its face. Next this ring 3 65 and of smaller diameter is arranged upon the support 4 a segmental die 6, concentric with the ring and forming a true circle and having its inner vertical face of the contour or profile of the tread or rim of the wheel and its outer 70 vertical face beveled.

7 is a concentric ring surrounding the male die and carried by the head or platen of its press.

8 is a wedge-shaped ring to be inserted in 75 the space between the ring 3 and segmental die 6, as seen in Fig. 2, and to be acted upon by the descent of the ring 7 to move the segmental die-sections radially, and thus close said die about the rim or tread of the wheel 80 to true the wheel.

As indicated in Fig. 3, the dishing is effected while the wedge-ring is omitted and then the dies are parted, the wedge-ring inserted between the ring 3 and the segmental 85 die and in line with the ring 7, and the male die and said ring 7 forced down, thereby further forcing the wedge-ring down between the ring 3 and segmental die and crowding the segments of said die up against the rim or 90 tread of the wheel, and thereby correcting all irregularities of the wheel without in any wise impairing the skin produced by the rolling action by which the wheel was made in the first instance. In this operation the ring 3 95 serves as an abutment for the wedge-ring in its action against the segmental dies. The outer ring 3, however, may be omitted, and in that case it would be well to make the wedge-ring somewhat heavier than is necessary when 100

the ring 3 is employed. There is a possibility of swelling or pinching up portions of the tread between the adjacent edges of the segments of the segmental die. To correct this defect, the support 4 for the segmental die is turned or shifted sufficiently to bring the face of the segmental die opposite the swelled or pinched-up portions of the tread, and then the wedge-ring is brought down again, so as to collapse the segmental die about the tread, and thus correct the tread in its entirety. The groove 5 permits the full descent of the wedge-die in order to apply the lateral or horizontal pressure to the segmental die equably throughout its full height, and thereby avoid any unequal lateral strains on either the segmental die or the supporting-ring 3. The pressure exerted upon the wheel by the segmental die is in radial lines, and hence the terms "lateral" and "horizontal" are to be understood relatively to the illustrations in the drawings.

What I claim is—

1. Apparatus for dishing and rounding steel car-wheels, comprising essentially a matrix and a complemental die by means of which a preformed wheel is dished, and a radially-movable segmental die arranged upon the matrix and surrounding the rim of the dished wheel thereon and having a face of the contour of the tread and flange of the wheel, and a ring operated by the descending complemental die to close the segmental die about the rim and flange of the wheel to round the same.
2. A matrix and a complemental die shaped to receive a preformed car-wheel, combined with a wheel-rounding die of circular form made up of segments having a profile of the flanged rim of the wheel and with a beveled back, and a beveled ring encircling the segmental die and adapted to close said segments about said wheel under the pressure of the male die, whereby by successive operations of the dies the wheel is dished and its rim or tread rounded, substantially as described.
3. A matrix and a complemental male die, having the profile of a dished car-wheel, combined with a wheel-rounding die of circular form made up of segments of the contour of the tread and flange of the wheel and having a beveled back and placed around the wheel

on the matrix and supported thereby, and a beveled ring encircling the segmental die and acted upon by the descent of the male die to close said segments about said wheel, whereby by successive operations of the dies the wheel is dished and rounded.

4. A matrix and a complemental male die shaped to dish a car-wheel, combined with a wheel-rounding die of circular form, in segments, a support for said segmental die, a surrounding ring for said segmental die arranged upon said support, and a wedge-ring actuated by the male die and adapted to enter the space between the segmental die and its surrounding ring and force said segmental die about the rim of the wheel.

5. A matrix and a complemental male die shaped to dish a car-wheel, combined with a wheel-rounding die of circular form, in segments, a support for said segmental die, a surrounding ring for said segmental die arranged upon said support, and a wedge-ring actuated by the male die and adapted to enter the space between the segmental die and its surrounding ring and force said segmental die about the rim of the wheel.

6. A matrix and a male die for making car-wheels, combined with a circular segmental die having a face contour corresponding with the tread of the wheel and a beveled back, a surrounding abutment-ring, and a wedge-ring adapted to work between the beveled back of the segmental die and its abutment-ring to forcibly close the segmental die about the rim or tread of the wheel.

7. Apparatus for dishing and rounding rolled-steel car-wheels, comprising a matrix, a male die, a circular segmental die adapted to surround the rim of the wheel when in the matrix and having a face of the contour or profile of the said rim, an abutment-ring and an interposed wedge-ring adapted to be operated by the male die to forcibly close the segmental die about the rim.

In testimony whereof I have hereunto set my hand this 4th day of October, A. D. 1904.

CHARLES T. SCHOEN.
